INVENTOR:
HAROLD F. PHILLIPS
BY Harry A. Birne
ATTORNEY

UNITED STATES PATENT OFFICE

HAROLD F. PHILLIPS, OF BELMONT, MASSACHUSETTS

PISTON AND SKIRT EXPANDING RING THEREFOR

Application filed February 10, 1932. Serial No. 592,009.

My invention has relation to improvements in piston and skirt expanding rings therefor and it consists in the novel features of construction more fully set forth in the specification and pointed out in the claims.

The present invention is an improvement over that shown in my Patent No. 1,806,416, dated May 19, 1931, and is directed to features of the expanding ring and means for securing said ring in the piston skirt that have been found desirable in practical operations. One of these new features is the inwardly bent terminals of the expanding ring which facilitate its insertion in and removal from the skirt of a piston. Another novel feature is the seating of the expanding ring in suitable recesses provided for this purpose in the piston skirt. The provision of special recesses to receive the expanding ring makes it possible to apply the expander to any type of piston regardless of its construction, as the recesses are specially provided to receive the expander and are located and shaped accordingly. These advantages, as well as others inherent in the invention, will be better apparent from a detailed description thereof in connection with the accompanying drawing, in which:

Figure 1 is a side elevation of an aluminium or alloy piston with my improved skirt expander ring applied thereto; Fig. 2 is a horizontal cross-section through the piston skirt taken on the line 2—2 of Fig. 1; Fig. 3 is a perspective view of a piston rigidly held in a vise while a reaming tool is cutting one of the recesses on the inside of the skirt for receiving the expander.

Referring to the drawing, P represents an aluminium or alloy piston of a common construction having its skirt 1 provided with a horizontal slot 2 immediately below the bottom ring land 3, the skirt also being provided with an inclined longitudinally extending slot 4 extending from slot 2 to the bottom of the piston skirt. The slot 4 is approximately midway between the wrist pin bosses 5, 5 and, as well understood, is provided for the purpose of allowing the skirt to contract circumferentially to compensate for the expansion caused by the heat during operation. As

pointed out in the patent above referred to, aluminium or alloy pistons have little resilience and soon become permanently set so that subsequent wear results in a teetering action of the piston during reciprocation thereof. 55

In order to impart resilience to the piston skirt so that it will hug the cylinder wall under all operating conditions an expanding element in the shape of an open ring 6 is inserted in the lower part of the skirt 1. In the principal embodiment of the invention the ring 6 has inwardly turned terminal portions 7, 7 immediately adjacent to which are the piston expanding parts 8, 8 and opposite to which is the piston expanding part 9. Between piston expanding parts 8, 8 and 9 are what may be termed ring-locking parts 10, 10, since the parts 10, 10 are adapted to be seated in oppositely disposed recesses 11, 11 formed on the inside of skirt 1. A simple method of forming the recesses 11, 11 is shown in Fig. 3, wherein the piston P is secured by a clamp C in a block B securely held in a vise V while a special rotary-acting reaming tool T is applied to the inner wall of the piston skirt for cutting the recesses 11, 11. The recesses 11, 11 are slightly longer than the ring-locking parts 10, 10, and in order that the ring-locking parts 10, 10 may have free access into the recesses 11, 11 said ring-locking parts and 80 the piston expanding parts 8 and 9 are separated by reentrant portions 12, 12 and 13, 13. In practice the ring-locking parts 10, 10 and the piston expanding parts, 8, 8 and 9 are described by the same circle, the diameter of which is the same as that of the outside surface of the piston skirt before the expander is inserted therein. The expander must thus be contracted, preferably by applying a pair of pliers to the terminal portions 7, 7 and 90 drawing the expander ends together, before it can be inserted into the piston skirt. On contracting the expander in this manner it may readily be placed within the skirt so that the ring-locking parts 10, 10 will enter the recesses 11, 11 and the ring-expanding parts 8, 8 and 9 will exert tension outwardly on the piston skirt. There will be no tension exerted on the piston skirt opposite the ring-locking parts 10, 10 as they will 95

100

not bear against the piston wall on account of the recesses 11, 11. Thus, the skirt will be expanded across the diameter at right angles to the bosses 5, 5 to take up the wear on the skirt wall as rapidly as it occurs. Obviously, there will be some expansion of the piston skirt in all directions, but the greatest amount of expansion will be, as just stated, where it will be most effective to prevent the wear 10 that results in a teetering of the piston in operation.

Having described my invention, I claim:

1. In combination with a piston having wrist pin bosses and a longitudinally slotted 15 skirt provided with transverse grooves formed in the inner peripheral surface of said skirt below said bosses, an expanding element disposed within said skirt, parts of said element having contact with and exerting pressure against said skirt and parts of said element expanding into said grooves to decrease the pressure on the skirt at these points.

2. In combination with a piston having wrist pin bosses and a longitudinally slotted 25 skirt provided with transverse grooves formed in the inner peripheral surface of said skirt below said bosses, an expanding element disposed within said skirt, parts of said element having contact with and exerting 30 pressure against said skirt and parts of said element expanding into said grooves to decrease the pressure on the skirt at these points, and tool receiving devices on the expanding element to facilitate handling the same.

35 In testimony whereof I hereunto affix my signature.

HAROLD F. PHILLIPS.
